UNITED STATES PATENT OFFICE.

CHARLES EISLER, OF NEWARK, NEW JERSEY.

SEALING-IN MACHINE FOR TUBES AND BULBS.

Application filed April 25, 1925. Serial No. 25,747.

This invention relates to a machine for sealing in the stems of radio tubes and the like and particularly to sealing in stems of the character set forth in my application Serial No. 6,527, filed February 3, 1925. That application covers a novel method of forming stems of the general character set forth in Jaeger Patent No. 729,182, May 26, 1903 and comprising generally a stem tube 10 with a flare for sealing to the bulb or tube neck, and an exhaust tube having its inner end bent laterally and fused to the side of the stem tube at a point removed from the sealed end thereof. The machine of the present application is of more general application, however as to certain of its features, and may be utilized, for example, for sealing in stems generally whether the tubulation or exhaust tube is fused directly to the bulb or 20 to the stem.

The object of the invention generally is a sealing-in machine including rotating heads of a novel construction and operation whereby the sealing-in, including the blowing off 25 of the surplus fused bulb neck, is effected in an entirely automatic and improved manner as compared with prior mechanisms of this general character. A further object is a novel stem tube support whereby the insertion and removal of the bulb parts are facilitated and the sealing-in expedited. A still further object is a mechanism of the above indicated character including a novel single point support for the stem while being sealed 30 into the bulb or tube whereby strains and breakages are substantially reduced during the sealing-in and the removal of the sealed-in bulb may be readily and quickly effected for centering the mount, if necessary, by the operator before the setting of the plastic seal. A still further object is the automatic removal of the stem support, if desired, after the fusing takes place and before the setting without exerting pull on the plastic seal. 40 My invention also contemplates a simplified revolving head structure whereby the parts may be economically produced and assembled and adjustments thereof facilitated for various sizes of lamps, and a simplified driving and control mechanism for effecting the intermittent and rotating movements.

For a better understanding of the above indicated novel features of the invention and others which will hereinafter appear, reference may be had to the accompanying draw-

ings forming a part of this specification, wherein:

Fig. 1 is a plan view of a sealing-in machine embodying my invention, more or less diagrammatically illustrated, 60

Fig. 2 is a sectional view of the machine along the lines 2—2 of Fig. 1,

Fig. 3 is a side view, partly in section, of a revolving head or spindle and associated parts, 65

Fig. 4 is a sectional view of the upper part of the stem support and cooperating parts, and

Fig. 5 is a sectional view of the lower part thereof. 70

Referring to the drawings where like numerals designate similar parts throughout, I have indicated my invention as embodied in a machine having a trough like stationary base or table 17, the latter being carried by 75 suitable standards, a rotatable spider or frame 10 which is mounted for intermittent rotation thereon and a plurality of rotatable heads 1 carried by the spider 10. In the particular embodiment herein illustrated there are six of these heads 1, although in practice as many of these heads may be provided as are desired. Intermittent movement of the spider 10 is effected through the medium of Geneva wheel 16 on the shaft 13 80 which is keyed to the spider, the Geneva wheel being driven by a cooperating driver 14 on a vertical counter-shaft 12, mounted in suitable bearings carried by the table 17. A worm gear 11 is mounted on the Geneva 90 driver shaft 12 and driven by the worm 15 on the driving shaft 2.

The various heads successively occupy the positions A, B, C, D, E, and F as the spider 10 is intermittently rotated, A and B being 95 the two front positions where the sealed tubes or bulbs are taken off and new tubes and stems are inserted, while at positions C, D, E the parts to be fused together are gradually heated and at the position F the concentrated heat applied to complete the fusing and the sealing of the bulb and stem together. The heads 1 with the bulbs and stems carried thereby are rotated about their axes at the positions C, D, E and F from the 100 driving shaft 2 by means of gears 3 keyed to the respective spindles and the rubber frictional drive wheels 4 which are carried by vertical counter shafts 7 rotatably mounted in the table 17, there being a rubber drive 4 110

adjacent each of the heating positions C, D, E, F. The shafts 7 project downwardly through the table 17 and carry on the under side a series of sprockets 6 around which passes an endless chain 5. One of these shafts 7 also carries on its lower end a spiral gear 9 which meshes with a cooperating spiral gear 8 on the drive shaft 2 for continuously rotating the drivers 4. The tubes and stems, assembled on the heads 1 in either position A or B, are intermittently carried around to the different heating positions C, D, E and F where heating flames are progressively caused to play thereupon, there being one heating flame 40 indicated in position C, two at position D, three at position E and eight at position F.

The rotating heads or holders 1 comprise a base 27 carrying two upright supports 29, and the latter in turn carry on their upper ends the bulb or tube support 30. The support 30 is capable of adjustment longitudinally of the supports 29 and may be fixed in any desired position by means of the set screws 31. Each base 27 includes a hollow shaft 27' which is journaled as indicated on the spider 10 and carries on its lower end the driving gear 3. Through the center of the base 27 and the hollow shaft 27' passes the stem support including a hollow sealing rod 19, and this rod carries within its upper end the stem adapter and support 32, 35. The stem adapter is of tubular form and closed at its lower end, and it consists of two parts, a lower part 35 which is screw-threadedly attached at its upper end to the interior of the upper end of the sealing rod 19 and an upper part 32 which is separably mounted within the upper part 35, the upper part being thereby removable without removing the whole support. The tubular member 32-35 may be adjusted longitudinally of the sealing rod by means of the adjustable nut 36 which is screw-threadedly attached to the upper end of the part 35 and engages the upper end of the sealing rod 19. A set screw 37 is provided for anchoring this nut in any adjusted position. The part 35 of the stem adapter for the greater portion of its length below the externally threaded portion at the top is made of smaller diameter than the interior diameter of this sealing rod 19, but at its extreme lower end it has an exact fit with the bore of the sealing rod. Longitudinal grooves 20' are provided along the surface of the lower end of the part 35 and similar grooves 20 are cut through the external threaded portions of the upper end thereof for a purpose herein-after set forth. In the particular embodiment herein, there are shown three such grooves equally spaced around both the upper and lower ends of the part 35 of the stem support. The stem adapter may be provided at its upper end with a circular flange 41

for engaging the flare of the stem tube and supporting the stem in the desired position, and the stem support is provided with a flaring opening at its upper end to facilitate the insertion of the stems with their exhaust tubes projecting downwardly and loosely therein and to permit ready removal of the lamp bulbs or tubes after the sealing-in operation.

The sealing rod 19 is provided on its lower end with a circular shoe 34 and between the latter and the end of the hollow shaft 27' there is disposed a spring 23 which normally urges the sealing rod and the shoe 34 in a downward direction against the circular track 24 carried by the table 17. The track 24 preferably has a bevelled off portion indicated at 24' in Fig. 3. This is for the purpose of causing an automatic lowering of the sealing rod 19 with the stem adapter 32, 35 at positions A and B to facilitate the taking off of the finished bulbs and placing of new parts thereon. An adjustable stop 25 is carried by the base portion 27 which cooperates with a collar 33 carried by the sealing rod at a point thereabove to limit the downward movement of the sealing rod. A key 26 in the base 27 cooperates with a long keyway 28 in the sealing rod 19 to effect the rotation of the rod 19 with the base 27, but at the same time permitting the longitudinal relative movement, if desired. The bevelled off portion 24' may begin immediately after leaving the position F and in that case, the weight of the filament stem 100 may be sufficient to lower or tilt the filament stem and mount with reference to the bulb, due to the fused and plastic condition of the seal. However, the operator upon removal of the bulb may, if necessary, slightly adjust 105 the stem with reference to the bulb to properly position the mount therewithin, since usually the seal is still slightly plastic when position A is reached. The operation of the sealing in machine is substantially as follows:

Upon the heads located at either A or B the operator inserts within the stem adapter 32, 35 a stem with its exhaust tube 43 extending loosely down into the stem tube support 30 and with its flare 44 resting upon the flange support 41. She also inserts over this stem and within the tube support 30 a tube 45 with its neck or skirt 46 extending down beyond the flare 44. With the parts thus assembled at position B, at the next intermittent operation the head 1 is automatically moved to position C where the driver upon coming into driving relation with the rubber wheel 4 at that position is rotated while a flame from the single burner 40 is caused to play upon the bulb or tube neck in the vicinity of the flare 44. At the next intermittent movement this head goes to position D where two or more flames are caused 130

to play upon the tube at the same point while it continues to rotate. At the next intermittent movement it goes to position E with further and preferably a greater number of flames playing upon the bulb neck and at position F concentrated flames are brought to bear upon the neck in the vicinity of the flare 44 which causes the fusing or welding of the flare 44 of the stem to the neck with considerable attenuation of the neck or skirt 46 down beyond the flare. At this position F a small continuously flowing blast of air from the nozzle 47 is directed up into the lower end of the hollow sealing rod 19 which blast of air passes upwardly in the direction of the arrows in Figs. 4 and 5 through the grooves 20' and 20 and to the space above the adjusting nut 36, the air pressure being sufficient to blow off the surplus glass as it is melted from the lower portion of the neck just below the flare 44. The tube 35 may be provided with a lateral opening 48 registering with a smaller opening 49 in the sealing rod 19 to keep the interior of the tube or bulb 45 in communication with the atmosphere, as such communication is always essential in sealing stems into bulbs. The head stays at position F long enough to effect the seal whereupon the intermittent operation takes place again and the head then goes to position A where the finished tube is removed to provide for the positioning of another bulb and stem to be sealed in. After leaving position F the stem support is automatically lowered by the shoe 34 running down the cam surface 24'. This automatically removes all support for and engagement with the stem, permitting the latter to yield freely during the cooling of the weld without hindrance from the support. Moreover, the lowering of the stem support at positions A and B facilitates the positioning of the lamp parts thereon.

The surplus neck 46 of the tube 45, if not broken before it reaches positions A and B is broken off by the operator whereupon it falls into the trough like table 17 and from there it is carried by a brush or rake 22 to an opening 21 in the table for dumping into a suitable receptacle.

Having thus described my invention, what I claim and desire to protect by Letters Patent is:

1. In a head for machines for sealing mounts in tubes or bulbs, a hollow rod having an opening through its wall, and a stem adapter secured near its upper end therein with a portion of the adapter extending above the rod and terminating in a seat for engaging the flare of the mount to be sealed in, the stem adapter being hollow to loosely receive the exhaust tube of the mount, the lower end of the adapter being of a diameter to fit the bore of the rod and pro-

vided with an external longitudinal slot constituting a passage for air to blow off the fused glass and also provided with an opening through its wall adapted to register with the opening through the wall of said hollow rod.

2. In a head for machines for sealing mounts in tubes or bulbs, a stem adapter provided with a seat at one end adapted to engage the flare of the mount, with an interior well open at the top and closed at its bottom to receive the exhaust tube of the mount and with thickened walls at its lower end formed with one or more external longitudinal slots, and with an opening through the unslotted portion of the thickened wall, and a hollow tube surrounding the adapter, fitting tightly the thickened walls thereof and provided with a wall opening registering with that in the wall of the adapter.

3. In a head for machines for sealing mounts in tubes or bulbs, a stem adapter provided with a seat at one end adapted to engage the flare of the mount, with an interior well open at the top and closed at its bottom to receive the exhaust tube of the mount and with thickened walls at its lower end formed with one or more longitudinal slots, and with an opening through the unslotted portion of the thickened wall, and a hollow tube surrounding the adapter, fitting tightly the thickened walls thereof and provided with a wall opening registering with that in the wall of the adapter, the adapter and tube having exterior and interior screw-threads securing them together.

4. In a head for machines for sealing mounts in tubes or bulbs, a stem adapter formed with a seat for the mount and a well to receive the exhaust tube of the mount, the adapter being closed at the bottom, an outer tube secured about the adapter, said tube and adapter being formed to provide passages for passage of air around the tube to points below the seat of the adapter and with a separate air passage from within the well through the walls of the adapter and tube.

5. In a sealing in machine a revolving head including a bulb support and a stem support adapted to support a stem in sealing relation with the bulb, said stem support including a hollow sealing rod, a stem adapter which is externally threaded near its upper end to engage with the internally threaded upper end of the sealing rod and an adjustable nut disposed about the threaded portion of the adapter for adjusting the adapter to different positions within the sealing rod.

6. In a sealing in machine for lamp bulbs or tubes, a revolving head including a bulb support, a stem support, said stem support being adapted to engage the stem only by the resting of the stem upon the upper end of the stem support, means for intermittently

- moving said revolving head from one position to another and means for automatically removing the stem support from engagement with the stem without exerting any
5 pull thereupon immediately after the seal is effected and before the plastic weld becomes set.
7. In a sealing in machine for lamp bulbs or tubes a trough like table, a revolute
10 frame thereon carrying a multiplicity of

revolute heads for sealing in lamp bulbs and fusing off the surplus necks of the bulbs during the sealing in operation, and a brush carried by the revolute frame and engaging the interior of the trough like table to convey the surplus glass to an opening provided in the table. 15

In testimony whereof, I have signed my name to this specification.

CHARLES EISLER.
